SAFETY RAZOR

John W. Clark, Washington, D. C., assignor of
one-third to Ethel Hudson Clark, Washington,
D. C.

Application March 16, 1944, Serial No. 526,732

9 Claims. (Cl. 30—70)

1

This invention has to do with safety razors of that type in which a thin flexible blade is used, which blade is associated with and manipulated by blade-engaging parts which will support and flex the blade; give sufficient external support to its cutting edge to maintain it in rigid condition for shaving action, and at the same time so guard the cutting edge of the blade as to prevent injury to the skin of the user.

One of its objects is to provide blade-engaging and holding parts which, when the blade is associated with them, will give an exact and precise positioning of the blade and ensure, in its final position, an accurate relation of the blade edge to the associated parts, the construction being such that the blade is prevented from lateral or longitudinal shifting as it takes its final position between the guard and cap of the razor.

A further object is to provide a construction in which the blade is flexed only at the edge portions of its area, the central area containing the slot or opening for engaging the handle post, stud, or rib of the guard and cap being held always in flat, unflexed condition and not subjected to bending strains. This is important, particularly with the thin blades now in use, as it makes the use of such blades possible without the danger of cracking the blade adjacent its central slot or opening, a difficulty which is encountered where the entire blade area is flexed and which frequently develops with thin blades.

Another object of the invention is to provide a simplified blade construction, while preserving its usability with razors now on the market, so that blade stamping may be readily and expeditiously accomplished without the need of complicated die formations to produce blade openings of particular and intricate design such as are now found in some blades.

In the new construction herein disclosed, a symmetrical design lending itself to rapid and low-cost production is provided, and one in which a high degree of blade edge protection and precise blade positioning is secured, so that blade life is prolonged and danger of nicks or cuts by reason of inaccurate blade positioning and imperfect blade edge protection is guarded against.

A still further purpose is to secure a construction in which rapid and complete drainage of shavings (meaning lather and beard particles) is accomplished so that the shaving areas of blade edges and their associated parts are cleared of shavings; clogging by reason of accumulations of lather and beard particles is avoided, and a sani-

2

tary condition of the razor maintained. The importance of this will be apparent. When a blade edge, guard teeth, and cap become clogged, clean cutting action of the blade is interfered with. This is particularly true if the soap used has a tendency to become ropy or stringy, as is true of some shaving mixtures now in use. This purpose is accomplished by so fashioning and relating the guard and other parts that free drainage beneath the cutting edge of the blade and away from the teeth and guard always takes place. This free and complete drainage, coupled with the fact that the parts of the razor are so designed and constructed that the major portion of the blade will be held between guard and cap practically sealed against the ingress of water or shavings, removes the necessity, which now exists with some razors, of releasing the blade for cleaning after shaving. Once clamped in place the blade can be safely left in position and need be removed only for the purpose of reversal or renewal.

In the detailed description which follows the structure and functions of the component parts of the razor for accomplishing the above-named purposes will be set forth, reference being made to the drawings which accompany and form a part of this disclosure.

In said drawings:

30 Figure 1 is a sectional view of the razor embodying my invention, the guard, cap, and blade being shown in separated position,

Figure 2 is a sectional view showing the guard, cap and blade in blade clamping position,

35 Figure 3 is an enlarged sectional view showing a portion of the guard, the cap, and the blade, in clamped position,

Figure 4 is a top plan view of the guard,

Figure 5 is a bottom plan view of the guard,

40 Figure 6 is a detail view of the guard teeth on an enlarged scale,

Figure 7 is a plan view of the inside face of the cap,

Figure 8 is a transverse sectional view of the cap,

45 Figure 9 is a longitudinal sectional view of the cap showing the blade engaging rib, and

Figure 10 is a plan view of the blade.

Numbers are used to designate the several parts in the drawings, and the same numbers identify the same parts in the several views.

Referring to the drawings, 10 indicates the razor guard having any desired number of teeth 12, although with this construction a less number 55 of teeth than is usual is preferable. The notches

13 between the teeth are of the same general form, though somewhat wider than usual, and fashioned to materially assist in drainage of shavings. The guard 10 has its central area 14 at each side of its median line flat defining a comparatively broad flat central zone comprising a liquid seal feature, as shown, so as to present a level surface upon which the central area or zone of the blade bears. Centrally disposed of the guard will be a depression or groove 15 which extends longitudinally thereof, and, as shown, has straight side walls terminating in a coned end portion to receive a complementary rib or equivalent projection on the cap, presently to be described.

The cap 16 is provided with a blade-receiving projection or rib 17 which has straight side walls and a coned tip in transverse cross section, and its base is accurately dimensioned to fit closely a complementary slot or opening in the blade. So constructed, the blade, when it is brought to its final position of engagement with the straight walls at the base of the rib 17 will be securely held against lateral play and its cutting edges precisely related to the guard 10 and the teeth 12 thereon. This is important for the reason that lateral blade shift or play distorts the relation of the parts and presents an asymmetrically positioned cutting edge in the assembled razor. Not only must lateral blade shift be prevented but it is necessary also that endwise play of the blade be prevented. This is accomplished by slightly coning the ends 18 of the rib 17 at the top, which coned portions terminate in straight wall portions, as shown in Figure 9, so that the ends of the blade slot will engage the rib ends 18 and longitudinal blade shift will be prevented. Preferably, the ends 18 of rib 17 will be such that the ends of the blade-slot will be brought into contact with the base of the ends 18 slightly in advance of the final engagement of the edges of the blade slot with the straight wall portions of the rib 17. The side edges of the blade-slot will engage the straight wall portions of the rib 17 and be in close contact therewith before any flexing of the blade takes place, and this engagement of the blade-slot with the rib will prevent buckling or bulging of the blade centrally of its length. In this connection, it is pointed out that the coned end portions 18 of the rib 17 and the slotted end portions of the blade represent critical construction, since these end portions engage so closely and accurately as to approach a longitudinally tensioning of the blade. The make-up of the rib 17 is such that its sectional areas, both as to length and width, increase in size from its top toward its base, the coned form permitting ready assembly of the apertured blade with the razor members, and ensuring the precise positioning of the blade when it engages the maximum dimensions at the base of the rib. In this disclosure the cap is provided also with the usual threaded handle post 19 to receive the handle, although it will be understood that other types of handle couplings may be used. The cap 16 will have a flat surface or zone 16' complementary to the flat area or zone 14 of the guard and slightly wider than the flat guard area so that the flexing or pivot points at which the edge portions of the blade bends are offset to a small degree, so as to ensure a complete and final flexing of the blade edge areas as the guard and cap are brought to final clamping position the rib 17 is the sole means for engaging and positioning the plate so

that there are no opposing blade engaging instrumentalities tending to distort the blade.

At each side of the flat central area 14 of the guard 10 are curved areas 20 over which the blade 22 extends and flexing of the blade will occur only at the outer blade areas, thus avoiding bending strains throughout the entire blade area and particularly in and about the slotted center. This edge flexing of the blade will take place from what may be termed pivot points 21 slightly removed from the blade edge, and takes place at a line through an uninterrupted blade area so far removed from the interrupted or slotted and flatly held area at the center of the blade that danger of blade cracking is practically eliminated.

With this construction the blade, when the guard and cap are clamped together, will be firmly held, in practically watertight or sealed condition, with the central area of the blade flat and undistorted, and the outer edges only of the blade subjected to flexing strains. This, as pointed out, is of very considerable advantage, particularly in connection with thin blades, for with this construction, bending strains and stresses are set up at the outer edge areas of the blade.

The blade 22 will be of the same general form as the usual thin blade, but will be provided with a straight slot 23 to engage the rib 17, heretofore described, or equivalent blade-engaging means at the sides and ends of the slot, and the necessity for cutting special slot formations, such as are now found in some blades, is done away with, the slot 23 being so dimensioned that it will take the blade-engaging means of present day razors, as well as being peculiarly adapted for the blade-engaging means herein disclosed.

It will be seen that, with this construction in which the central area of the blade containing the slot is clamped between the two flat surfaces on the guard and the cap, there is no distortion of the slot in the blade due to bending, as is the case where the entire blade is flexed. This permits the very accurate positioning of the blade and a precise engagement between the blade slot and the rib or equivalent projections which engage that slot. By such construction the initial aligning and positioning of the blade on the rib 17 in combination with its coned critical ends 18 guides the blade 22 to its final positioning, and it is held, as pointed out, against either lateral or longitudinal shift. This positioning of the blade by means of the rib 17 avoids distortion of the blade such as may develop where blade positioning is secured by marginal or outside positioning means such as end or corner lugs, in connection with which the slightest inaccuracy causes buckling of the blade with resultant distortion of the cutting edge. Further, the rib 17 in close engagement with the aperture 23 in the blade, positions the blade with precision and ensures proper relation of its cutting edges to the razor members.

In order to obtain complete and easy clearance of shavings from the razor, there is provided in the upper face of the guard the grooves 24 which are formed partly in the teeth 12 and partly in the body of the guard 10, as shown.

The edge of the blade 22 will project over the groove 24 in close protective relation to teeth 12 of the guard 10, as shown, but the shavings can escape readily from beneath the edge of the blade into the groove 24. The rear ceiling walls of the notches 13 will be sloped rearwardly and downwardly from the point of blade contact.

The side walls of the notches 13 are flared outwardly from the point of blade contact so as to provide laterally flared channels 25, so as to form free, unobstructed drainage channels rearwardly from the notches 13 to the surface of the guard 10. Shavings collected at the edge of the blade will pass beneath the blade to the groove 24, and thence, through the notches 13 with their inclined rear walls, will flow to the inclined flaring channels 25 in thinned-out streams and be readily and completely delivered, so that no clogging of the teeth or the blade edge can occur. This construction is of particular advantage in connection with shaving mixes or compositions which have any tendency to ropiness which might cause objectionable collection and jamming of shavings beneath the blade edge. Further, with the groove 24 and the channels 25 shown and described, the matter of washing the shavings from the razor is very much expedited, for the construction is such that under flow of water stream, the shavings will be completely washed away and the necessity for opening the razor or using other means for shavings removal is done away with. To further assist in drainage and clearance of shavings, the teeth 12 are rounded or crowned on their upper surfaces as at 26 so that no flat or abrupt surfaces or edges on which shavings might collect and clog are present, and complete and ready washing off of shavings from the assembled parts under a flowing stream of water without the necessity of opening or loosening such parts, is ensured.

This disclosure will suggest to others mechanical variations from the specific structure here shown for the purpose of illustration, and it is to be understood that such changes may be made without departing from the range of the invention, which is limited only as set forth in the appended claims.

I claim:

1. A safety razor comprising a member having a longitudinally and centrally disposed flat blade-engaging area; a second member having a complementary flat blade-engaging area to clamp the central portion of a blade against the first-named area in flat undistorted position; a longitudinally disposed centrally placed rib on one of said members and a complementary recess on the other of said members, said rib having straight side wall portions and straight end wall portions, said end wall portions being only slightly coned to engage the ends of the slot in the blade slightly in advance of the engagement of the side wall portions with the slotted blade, and curved blade-engaging edges on said members adjacent the flat areas to engage and flex the outer edge portion of a blade.

2. A safety razor having a handle, cap and guard members and a flexible double edge blade, said cap having means adapted to engage the handle whereby the cap, the blade and the guard may be clamped together, said blade having an aligning portion defining a slot located in the longitudinal central zone of said blade, said cap member having a continuous aligning projection extending lengthwise of and located on the central longitudinal zone of said cap member, said projection being elongated and having critical end portions which are adapted to accurately engage the ends of the aligning slot of the blade, said guard member having a continuous elongated recess located in its central zone to receive a portion of said aligning projection extending from said cap member, the cap and guard mem-

bers having plain flat portions extending from end to end and extending transversely of said members throughout major portions of their opposed surfaces, said positioning and aligning means being of less length than the cap, blade and guard members, thereby defining a sealing area entirely surrounding said positioning and aligning means to prevent the free entrance of water or other fluids to the aligning means or to the clamping portions of the blade.

5. A safety razor guard, said guard being oblong and rectangular and having a flat plain upper portion merging into curved portions on its longitudinal edges, a toothed portion extending in the same general direction as said curved portion, a grooved portion extending transversely of the teeth of said toothed portion and bordering on said curved portion, and flow passages extending from between the teeth of the toothed portion and from said curved portion backwardly beneath said curved and flat portions.

10. A safety razor guard, said guard being oblong and rectangular and having a flat plain upper portion merging into curved portions on its longitudinal edges, a toothed portion extending in the same general direction as said curved portion, a grooved portion extending transversely of the teeth of said toothed portion and bordering on said curved portion, flow passages having rearwardly and downwardly inclined walls extending from between the teeth of the toothed portion and from the curved portion backwardly beneath said curved and flat portions.

15. A safety razor guard, said guard being oblong and rectangular and having a flat plain upper portion merging into curved portions on its longitudinal edges, a toothed portion extending in the same general direction as said curved portion, a grooved portion extending transversely of the teeth of said toothed portion and bordering on said curved portion, laterally flared flow 20 passages having rearwardly and downwardly inclined walls extending from between the teeth of the toothed portion and from the curved portion backwardly beneath said curved and flat portions.

25. A safety razor comprising a member having a longitudinally and centrally disposed flat blade-engaging area; a second member having complementary flat blade-engaging areas to clamp a blade against the flat area of the first-named member in flat undistorted position; an extended longitudinally disposed continuous rib centrally placed in the flat area of one of said members to engage a slotted blade and a continuous longitudinally disposed complementary recess on the other of said members, said rib forming the sole connection between blade and razor members to hold the blade against longitudinal and endwise movement with its edges in precise relation to the edges of said blade holding members, the flat areas of said member in cooperation with the blade defining a liquid seal to exclude water from between the members and the blade, and curved blade-engaging edges on said members adjacent the flat water excluding areas to engage and flex the outer edge portions of a blade.

30. A safety razor comprising a member having a longitudinally and centrally disposed flat blade engaging area; a second member having a complementary flat blade engaging area to clamp a blade against the flat area of the first-named member in flat undistorted position; an extended longitudinally disposed continuous rib having straight side and end walls centrally

placed in the flat area of one of said members to closely engage a slotted blade and a continuous longitudinally disposed complementary recess on the other of said members and forming the sole connection between the blade and the razor members to hold the blade against longitudinal and endwise movement with its edges in precise relation to the edges of said blade holding members, the flat areas of said members in cooperation with a blade defining a liquid seal to exclude water from between the members and the blade, and curved blade-engaging edges on said members adjacent the flat water excluding areas to engage and flex the outer edge portions only of a blade.

8. A guard member for safety razors having a curved portion over which a blade may be flexed, alternating teeth and notches in the edge of said curved portion, downwardly sloping ceiling walls and laterally flared side walls extending rearwardly from the notches and defining rearwardly expanding flow passages on the underside of said guard, the upper side of said guard having a groove in communication with the notches to receive shavings from a blade and deliver them to the notches and flow passages.

9. A guard member for safety razors having a

curved portion over which a blade may be flexed, alternating teeth and notches in the edge of said curved portion, downwardly sloping ceiling walls and laterally flared side walls extending rearwardly from the notches and defining rearwardly expanding flow passages on the underside of said guard, the upper side of said guard having a groove spanning the notches and disposed beneath the edge of a blade to receive shavings from a blade and deliver them to the notches and flow passages.
